UNITED STATES PATENT OFFICE

148,090

DESIGN FOR A COMBINED ASH TRAY AND FIGURE

Max Reikosky, Trenton, N. J.

Application May 23, 1945, Serial No. 119,687

Term of patent 3½ years

(Cl. D85—2)

To all whom it may concern:

Be it known that Max Reikosky, a citizen of the United States of America, residing at Trenton, in the county of Mercer and State of New Jersey, has invented a new, original, and ornamental Design for Combined Ash Tray and Figure, of which the following is a specification, reference being had to the accompanying drawing, forming part thereof.

Figure 1 is a top plan view of a combined ash tray and figure embodying my new design.

Figure 2 is a front elevational view thereof.

Figure 3 is a side elevational view thereof.

I claim:

The ornamental design for a combined ash tray and figure, as shown.

MAX REIKOSKY.
